UNITED STATES PATENT OFFICE.

THEODORE A. ROSS, OF CHICAGO, ILLINOIS, ASSIGNOR OF ONE-THIRD TO STEVE PAPPAS AND ONE-THIRD TO THEODORE DADAS, BOTH OF CHICAGO, ILLINOIS.

OIL BURNER.

Application filed June 20, 1927. Serial No. 200,071.

This invention relates to improvements in oil burners and its object is to provide a burner that is efficient in operation, durable and clean since it operates without forming 5 carbon deposits.

With the foregoing and other objects in view the invention consists in the combination and arrangement of parts to be herein-after fully described, particularly pointed 10 out in the appended claims and illustrated in the accompanying drawings which form a part of this application and in which—

Fig. 1 is a view of the burner in elevation and partly in section to afford a better illustration.

Fig. 2 is an inverted plan view of the steam dome and mechanism contained therein and is taken on line 2—2 of Fig. 1.

Fig. 3 is an enlarged vertical sectional 20 view of Fig. 1.

Fig. 4 is a cross section on line 4—4 of Fig. 3.

Fig. 5 is a cross section on line 5—5 of Fig. 3, looking in a direction opposite to 25 that in which Fig. 4 is taken.

Like reference characters denote corresponding parts throughout the several views.

This burner is of the type adapted for disposal upon the fuel grate in the combustion 30 chamber of steam boiler furnaces, hot water boiler furnaces, hot air furnaces, etc., etc., and it comprises the base plate 1 that rests directly upon the fuel grate and supports the elbow-like air pipes 2 at their lower

35 ends, said plate 1 being perforated in alignment with the pipe bores to permit the intake of air into the said pipes through the grate openings and through the plate. The said air pipes are jacketed with water and

40 steam jacket 3 which is formed with the integral flared or bell shaped portion 4, said jacket 3 being formed also with the rib 5 that supports the vertical steam passageway 6 integral with and depending from the

45 steam chest 7 that is screwed into supporting engagement with the removable center plate 8 of a water and steam dome 9, connected by pipe 9^a with jacket 3.

40 Into diametrically opposed perforations 50 in the steam chest the ends of a steam pipe 10 are tapped, said pipe extending through

the plate 8 into the dome 9 and rising almost to the apex thereof and being curved or arched at its highest point and formed with an intake opening 11 spaced away from the 55 dome apex. Secured to the pipe 10 are the support pins 12 for the open ended cylindrical shield 13 for the float 14 disposed therewithin, said shield being formed with a plurality of perforations 15. Depending 60 from the float is a stem 16 that extends through a perforation or seat 17 in one end of the hollow vertical column 18 into said column, said stem carrying a valve 19 capable of closing the said perforation 17 in said column when the float is spaced a certain distance thereabove.

The column 18 extends through the steam chest 7 and steam passageway 6 and beyond 70 said members and is supported by the steam chest, said steam passageway 6 being separated at its mouth 20 from the column 18 by the collar 21 formed with the spaced ports 22 equidistant one from the other. The column 18 beyond the passageway 6 75 is flared outwardly to form a water reservoir and passageway 23 into which a pipe 24 leads that supplies water under pressure, in cities the purpose being to connect the pipe 24 to the city mains. An oil pipe or 80 liquid fuel pipe 25 extends into the lower end of the reservoir and longitudinally through the center thereof to a point below the mouth 20 of the passageway 6 where it opens into a horizontal head 26 formed with 85 four radial openings arranged below the steam ports 22 in collar 21, so that a vertical plane in which any two of the oil openings would lie would also contain two of the steam ports.

Secured to the reservoir 23 is a flame spreader 27 formed with a horizontal flange 28, the free edge thereof being upturned so that it may receive and retain liquid fuel and serve as a priming cup and below said flange are two gas jets 29 which will ignite any fuel that may pass from the fuel ports in the head 26 or that may drip or fall to the base plate 1. The dome 9 is formed with a plurality of air passageways 30 and with a 100 plurality of spaced vertical recesses 31.

In operation the oil in the priming cup

28 is ignited, the gas ignited at the jets 29 and a small amount of oil admitted through the pipe 25 which passing out through the radial openings in the head 26 5 will burn upon or about the flame spreader and so get the burner hot. A small stream of water is now admitted through the pipe 24 which will fill the reservoir 23 and pass up and about the head 26 and out through 10 the opening 17 in the column 18 into the dome 9. The heat from the burning fuel will form steam in the dome 9 and water passing from the dome 9 through pipe 9^a will fill the water jacket 3 and its flared 15 portion 4.

Steam from the dome 9 will pass through the opening 11 in the pipe 10 and through said pipe into the steam chest 7 and through said steam chest 7 and through the passageway 6 out through the ports 22 20 and mix with the oil from head 26 thus heating and vaporizing the same, this vapor then being consumed in the flame of the burner. This flame spread by the member 27 will envelop the jacket 3, 4 and air pipes 25 2 and pass up and about the dome 9, in the recesses 31 thereof which facilitate heating of the water therein and vaporizing the same. Air passing through the many air pipes and water being fed into the dome will prevent 30 too great heat development while an excess of water will be prevented by the float which would then rise and close the port 17 in the column 18. An overflow pipe, not shown, will lead from the plate 1. The oil from 35 the ports in the head 26 receives the dry steam from the steam ports 22 which vaporizes the oil in the atmosphere raising its efficiency as a fuel to a very high degree.

What is claimed is:

1. In an oil burner, a base plate, air pipes 40 leading up and toward each other from said base plate, a water jacket for said air pipes, a steam chest supported by said water jacket, a steam passageway integral with said steam chest, a column extending through said steam chest and said steam passageway and formed with a valve in one end, a dome carried by said steam chest and receiving the valved end of said column, a water pipe connecting said dome and water jacket, a steam pipe opening into said steam chest and in 45 said dome at the apex thereof, a valve float in said dome operatively controlling the valve in said column, a water reservoir communicating with said column, a liquid fuel pipe extending longitudinally through said water reservoir and opening horizontally through the sides thereof, steam ports located in the mouth of said steam passageway 50 above the mouth of said liquid fuel pipe, a flame spreader carried by said water reservoir, and gas jets arranged below said flame spreader.

2. In an oil burner, a base plate, air pipes 65 supported upon said base plate, a water

jacket for said air pipes, a steam chest carried by said water jacket, a dome carried by said steam chest, automatic water supply means for said dome associated with said steam chest, said means comprising a column 70 extending through said steam chest, a steam pipe connecting said steam chest and dome, liquid fuel supply means associated with said column and comprising a head formed with ports opening through the sides 75 of said column, steam exhaust ports for said steam chest disposed immediately above the said head, a flame spreader disposed about said column below said head, gas jets arranged below said flame spreader, and a 80 water pipe connecting said dome and water jacket.

3. In an oil burner, a base plate, air pipes supported upon said base plate, a water jacket for said air pipes, a steam chest carried by said water jacket, a dome carried by said steam chest, a water pipe connecting said dome and water jacket, automatic water supply means for said dome associated with said steam chest, a steam pipe connecting 90 said steam chest and dome and opening into both of said members, steam outlet ports for said steam chest, liquid fuel supply means comprising ports opening immediately below said steam outlet ports, a flame spreader 95 below said fuel outlet ports, and gas jets arranged below said flame spreader.

4. In an oil burner, a base plate, air pipes supported upon said base plate, a water jacket for said air pipes, a steam chest carried by said water jacket, a dome carried by said steam chest, air pipes for said dome, a water pipe connecting said dome and water jacket, automatic water supply means for said dome associated with said steam chest, said means comprising a column 100 extending through said steam chest, a steam pipe connecting said steam chest and dome and opening into both, the opening of said steam pipe in said dome being above the normal water line therein, liquid fuel supply means associated with said column and comprising a head formed with ports opening through the sides of said column, steam exhaust ports for said steam chest disposed above said head, a flame spreader disposed about said column below 110 said head, and gas jets below said flame spreader.

5. In an oil burner, a base plate, air pipes supported upon said base plate, a water jacket for said air pipes, said jacket comprising a bell-shaped portion spaced from said air pipes, a steam chest carried by said water jacket, a dome carried by said steam chest, air pipes for said dome, a water pipe connecting said dome and water jacket, automatic water supply means for said dome associated with said steam chest, said means comprising a vertical column 120 extending through said steam chest, a steam pipe con-

necting said steam chest and dome and opening into both, liquid fuel supply means associated with said column and comprising a head formed with ports opening through the sides of said column, steam exhaust ports for said steam chest disposed above said head, a flame spreader disposed about said

column below said head, and gas jets below said flame spreader.

In testimony that I claim the foregoing ¹⁰ as my own I have hereto affixed my signature.

THEODORE A. ROSS.
